UNITED STATES PATENT OFFICE

ACHILLE PIQUEREZ, OF NEW YORK, N. Y.

WINDOW

Application filed July 18, 1928. Serial No. 293,551.

This invention relates to improvements in windows and more particularly to the type of windows having upper and lower sliding sashes.

5 The primary object of my invention is to provide a window structure having sashes that can be raised and lowered by the usual sash weights and cords and which may be turned on a horizontal axis when brought 10 into their extreme lowered position to facilitate the reversing of the same to present both sides of the window pane for cleaning on the inside.

Another object of my invention is to provide a window which does not necessitate the climbing out on the window sill or sitting upon the same to clean both sides of the pane of glass which has proven very dangerous to those who must perform this work.

20 Another object is to provide a window that has the appearance of an ordinary window but has upper and lower sashes which can be swung on a horizontal axis without requiring the actuation of a number of parts.

25 A still further object of my invention is to provide a window having sashes that can be easily removed when it becomes necessary to take a large object such as a safe, piano or the like through the window.

30 With these and other objects in view, the invention resides in certain novel construction and combination and arrangement of parts, the essential features of which are hereinafter fully described, are particularly 35 pointed out in the appended claims, and are illustrated in the accompanying drawing, in which:—

Figure 1 is a perspective view of my improved window showing the lower sash partly turned.

40 Figure 2 is a vertical sectional view taken on the line 2—2 of Figure 1.

Figure 3 is a vertical longitudinal sectional view taken on the line 3—3 of Figure 2.

45 Figure 4 is a horizontal sectional view taken on the line 4—4 of Figure 2.

Figure 5 is a vertical sectional view similar to that of Figure 2 but showing the lower sash raised and the upper sash lowered and 50 swung on its horizontal axis.

Figure 6 is a horizontal sectional view taken on the line 6—6 of Figure 2.

Figure 7 is a similar view taken on the line 7—7 of Figure 5.

55 Figure 8 is a detail perspective view of one of the sash members with one of the locking bars in a drawn out position.

Figure 9 is a detail perspective view of a part of the frame showing the slots in the 60 parting strips.

Referring to the drawings by reference characters, the numeral 10 designates my improved window in its entirety which includes a frame structure 11 embodying a sill 12, and having sets of spaced parting strips 13 and 14 attached to the inner vertical sides thereof, which provide grooves 15 and 16 therebetween, to slidably receive pairs of locking bars 17 and 18 respectively, which pivotally support upper and lower sashes 19 and 20. 70

Provided in the inner sides of the parting strips are upper and lower longitudinal slots 21 and 22 respectively, having offset portions 23 and 24 at their lower ends, while the upper ends of the same open onto the side faces of 75 the strips as at 25 and 26 to permit sets of guide pins 27 and 28, which extend from the sides of the locking bars 17 and 18 to be inserted into their respective slots.

The upper and lower sashes 19 and 20 are 80 provided with recesses 29 and 30 along the side rails thereof which slidably receive the locking bars 17 and 18 when in locked sliding position, to allow the sashes to be raised and lowered on a vertical plane under normal 85 conditions.

Hingedly mounted as at 31 to the sill 12 is a sash stop 32 which under normal conditions lies in the downward path of the sashes to prevent the guide pins, carried by the locking bars, from entering the offset portions 23 and 24 of their respective slots. 90

For pivotally supporting the upper and lower sashes in their respective opposed sets of sliding bars 17 and 18, I provide pivot pins 95 33 and 34 which have their outer ends threaded into the side bars and their other ends free within openings 35 and 36 in the side rails of the respective sashes. By fixedly securing the pivot pins to the slide bars and leav- 100

ing them free with the sashes, the slide bars may be moved to extended positions beyond the side rails of the sashes to release them for swinging movement in a manner to be hereinafter fully described.

For supporting the sashes in their various adjusted sliding positions, I employ the usual sash cords 37 which have one of their ends connected to the upper ends of the slide bars of the respective sashes, while weights 38 are carried by their other ends, the sash cords being trained over pulleys 39 journalled at the top of the frame.

From the description, it can be readily understood that when it is desired to clean the panes of either the upper or lower sashes on both sides, the lower sash 20 must be raised a distance, far enough, to allow the sash stop 32 to be swung out of the downward path of the sashes and into the position as shown in full lines in Figures 1 and 2 of the drawing.

Assume that it is desired to clean the pane of the lower sash, whereupon the lower sash 20 is dropped to its lowermost position at which time the bars 18 slide out of the recesses 30 in the side rails of the sash and into the grooves 16, as the guide pins 29 ride into the offset portions 24 of the slots 22. The lock bars 18 are now clear of the side rails of the lower sash and the same is free to be swung on its horizontal pivot pins 34. After the pane of the lower sash has been cleaned on both sides, the same is swung back to normal vertical position so that the recesses 30 register with the grooves 16 and as the sash is raised the guide pins ride out of the offset portion, back into the slots 22 which cause the slide bars to again be moved into locking engagement with the side rails of the lower sash.

The lower sash is then raised to its uppermost position to allow the upper sash 19 to be brought to its lowermost position, and as the parts of the upper sash are of the same construction as the lower sash and move in the same manner as explained for the lower sash, it is not believed necessary to again describe the operation of the same.

After the upper and lower sashes have been cleaned and brought back to normal locked position and before the lower sash has been lowered, the sash stop must be swung back to normal position as shown in dotted lines in Figures 2 and 5 of the drawing to prevent the sashes from being lowered to unlocked position.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In a window construction, a window frame, sets of opposed locking bars slidably mounted in said frame, upper and lower sashes pivotally mounted in the respective sets of opposed locking bars, a sash stop pivoted to the sill of said frame in the path of downward movement of said sashes, means effecting a locking connection between the upper and lower sashes and their supporting locking bars when said sash stop is in the path of downward movement thereof for sliding therewith, and means for automatically releasing said sashes from engagement with their lock bars upon swinging of said sash stop out of the path of downward movement of said sashes and upon movement of said sashes to the limits of their downward movement, said sashes adapted to be lowered one at a time to allow the same to be swung on their pivotal axis.

2. In a window construction, a frame, sets of bars slidably mounted in said frame, upper and lower sashes pivoted to the respective sets of bars, means for locking said sashes against swinging movement to slide in said frame under normal conditions, a sash stop member movable into and out of the path of downward movement of said upper and lower sashes, and means for automatically effecting the release of said locking means when said stop member is moved out of the path of downward movement of said upper and lower sashes, and either of said sashes has been lowered to its lowermost position, to allow the lowered sash to be turned on its pivot relative to its supporting set of bars.

3. In a window construction, a frame, opposed locking bars slidably mounted in said frame, a sash pivoted to said locking bars, a sash stop hinged to said frame for swinging movement into or out of the path of downward movement of said sash, coating means between said lock bars and said frame for locking said sash to said lock bars by causing said lock bars to enter recesses in the side rails of said sash, and means for releasing said lock bars from said recesses upon the movement of said sash stop out of the path of downward movement of said sash and upon lowering of said sash to the limit of its downward movement to allow said sash to be turned on its pivotal axis.

4. A window construction comprising a frame having spaced parting strips along the inner sides thereof and a sill at the bottom, sets of longitudinal slots provided in said parting strips having offset portions at the lower ends thereof, sets of bars slidably mounted between said parting strips, pins extending from said bars into the respective slots, upper and lower sashes pivoted to the respective sets of sliding bars by pivot pins carried thereby, the longitudinal slots in said parting strips serving to extend said sets of

- bars into grooves provided in the sides of said sashes to lock the sashes against swinging movement, and a sash stop hingedly mounted on said sill in the path of downward movement of said sashes for limiting the downward sliding movement of the same, said sash stop adapted to be swung to a position out of the path of downward movement of said sashes, to allow either of said sashes to be lowered upon said sill to cause said pins to enter the offset portion of said slots to retract said bars from the grooves in said sashes to facilitate the turning of the lowered sash about its pivotal axis.
- 5 5. In a window construction, a frame, sets of opposed bars slidably mounted in said frame, upper and lower sashes pivoted to said bars, co-acting means between said bars and said frame for locking said sashes to said bars by causing said bars to enter recesses in the side rails of said sashes, a sash stop hinged to said frame for swinging movement into and out of the path of downward movement of said sashes, automatic means for releasing said bars from said recesses upon movement of the same to their lowermost position, when said sash stop is out of the path of downward movement of said sashes to allow the swinging of the lowered sash on its pivotal axis.
- 10 20 25 30 In testimony whereof I have affixed my signature.

ACHILLE PIQUEREZ.
